United States Patent Office

Des. 183,070

Patented June 17, 1958

183,070

SPRAY GUN

Ward J. Stillson, Lansing, Mich., assignor to Food Machinery and Chemical Corporation, San Jose, Calif., a corporation of Delaware

Application October 10, 1957, Serial No. 48,058

Term of patent 14 years

(Cl. D62—2)

FIG. 1

FIG. 2

Fig. 1 is a perspective of a spray gun embodying my new design, particularly illustrating one side of the gun.

Fig. 2 is a perspective of the spray gun showing the side of the gun opposite to that shown in Fig. 1.

I claim:

The ornamental design for a spray gun, as shown.
